(57) **CLAIM**

The ornamental design for a square ratchet head with square plug and square body, as shown and described.

DESCRIPTION

FIG. 1 is a rear, left, top perspective of a square ratchet head with square plug and square body according to my new design.

FIG. 2 is a front, right, bottom perspective of the square ratchet head with square plug and square body thereof.

FIG. 3 is a front view of the square ratchet head with square plug and square body thereof.

FIG. 4 is a rear view of the square ratchet head with square plug and square body thereof.

FIG. 5 is a left-side view of the square ratchet head with square plug and square body thereof.

FIG. 6 is a right-side view of the square ratchet head with square plug and square body thereof.

FIG. 7 is a top view of the square ratchet head with square plug and square body thereof; and,

FIG. 8 is a bottom view of the square ratchet head with square plug and square body thereof.

The broken lines are for illustrative purposes only and form no part of the claimed design.
